UNITED STATES PATENT OFFICE.

FRANK C. WILLIAMS, OF WILDWOOD, NEW JERSEY, ASSIGNEE TO THE SAFETY BLOCK SIGNAL COMPANY, A CORPORATION OF DELAWARE.

TRAIN STOPPING AND SPEED-CONTROLLING MECHANISM.

Application filed May 20, 1922. Serial No. 562,280.

To all whom it may concern:

Be it known that I, FRANK C. WILLIAMS, a citizen of the United States, and a resident of Wildwood, in the county of Cape 5 May and State of New Jersey, have invented certain new and useful Improvements in Train Stopping and Speed-Controlling Mechanisms, of which the following is a specification.

10 My invention relates to an automatically operating train stopping and speed controlling mechanism whereby a train will be automatically stopped if there is another train in the block next in advance thereof, if 15 the first mentioned train is proceeding at a predetermined low rate of speed (say, for instance, four miles an hour) and wherein the train will be under the automatic control of a speed responsive mechanism and 20 will be permitted to proceed at a moderate rate of speed (as for instance thirty miles an hour) upon entering a block in which the signal is set for at 45° or "caution" position indicative that there is a train in 25 the block next in advance of that block in which the train is about to enter. A train stopping mechanism of this kind is clearly disclosed in and forms the subject-matter 30 of my co-pending application, Serial No. 192,636, filed September 22, 1917.

It is the object of the present invention to provide a mechanism which will operate in the manner above indicated and beyond the control of the operator or engineman whenever he attempts to speed up above the predetermined speeds under the conditions above outlined; that is to say, the mechanism will automatically operate if the engineer attempts to enter or proceed in the 40 block at the beginning of which there is a "danger" signal at a speed greater than four miles an hour, or attempts to proceed in a block in which the signal is set at 45° at a speed greater than a moderate speed, as 45 for instance, thirty miles an hour. It is to be understood that these speeds above referred to are merely by way of example and the devices may be set or adjusted to so operate at any predetermined speed.

50 A further object of my invention is to insulate one or more trucks on a train, and preferably a truck of the tender, effectively and completely from the rest of the train.

A further object of my invention is to so 55 connect a battery of a train stopping mech-

anism to a truck and to the magnet, the de-energization of which is effective to actuate the brake applying mechanism that any grounding of the wires between the battery and the said magnet or the breaking down 60 of any insulation between the insulated truck and the rest of the train will result in the automatic application of the brakes to stop the train.

A further object of my invention is to 65 provide a construction in which the king-pin by which the car or tender is attached to a truck and upon which the truck turns with respect to the car or tender is insulated from the truck or from the car, or from either 70 or both, and to so arrange the circuits operating the automatic stopping mechanism that any breaking down of the said insulation between the king-pin and the truck will result in an automatic application of the 75 trucks.

Further objects of my invention will appear in the specification and claims below.

Referring to the drawings in which the same reference characters are employed 80 throughout the various views to designate the same parts,

Fig. 1 represents diagrammatically one form of carrying my invention into effect and particularly illustrates the way in 85 which the circuits are disposed with respect to the train trucks, the automatic stopping mechanism and the tracks; and

Fig. 2 is a longitudinal sectional view through a truck or tender floor showing the 90 king-pin and one way in which the same may be insulated, and also showing how a truck is insulated from the other parts of the train.

Referring to Fig. 1, the track consists of 95 a pair of rails 1, 2, divided by insulation 3 into blocks 4, 5 and 6. These blocks are all alike and therefore a description of block 5, which is completely shown, will suffice, generally speaking, for a description of blocks 100 4, 6, or any other blocks into which the track may be divided. At the end of block 5 is a battery 7, having one side connected by wire 8 to track 1 of that block and its other side connected by wire 9 to track 2 of said 105 block. At the beginning of block 5 is a relay 10 connected by wires 11 and 12 to the rails 1 and 2 respectively. Separated by a predetermined distance X but relatively 110 near the end of block 5, there is set into the

tracks relatively short rail sections 13 and 14, one in each track respectively and the said section 13 is shown as separated from the track 1 by insulations 15-15 and the 5 short section 14 is separated from track 2 by similar insulation 15-15. Around the short insulated rail section 13 is a bond wire 16 and around the short rail section 14 is another bond wire 17. From the 10 above it will be seen then that from battery 7, a circuit is normally flowing through wire 8, track 1 of block 5, bond 16 back to track 1 of block 5, thence by wire 11 to relay 10 and thence by wire 12 to track 2 of block 5 15 and then around the short insulated rail section 14 by bond wire 17 to track 2, and thence by rail 9 back to battery. In this way then, with no train within the block, battery 7 keeps relay 10 energized and the armature 18 thereof held up as is clearly indicated in 20 Fig. 1. It will also be evident that the instant a train enters block 5, the circuit from battery 7 above outlined will be short-circuited by the wheels of the train and substantially no current will flow through wire 11, relay 10 and wire 12, thus causing a de-energization of the relay magnet 10 and a 25 consequent dropping of the armature 18. Thus, whether the magnet 10 is energized or de-energized depends upon the presence of a 30 train in block 5. The arrangement of block 4 is like that of block 5 and in Fig. 1 is shown the relay magnet 19 similarly connected by wires 20 and 21 with the rails 1 35 and 2 respectively of block 4. This relay 19 is arranged to hold up its armature 22 when block 4 is clear or unoccupied, in the same way that relay 10 holds and controls its armature 18. Block 6 is like block 5 in that 40 at the end thereof is a battery 23 having its opposite sides connected by wires 24 and 25 with the tracks 1 and 2 respectively of block 6, the block being also provided with short rail sections 26 and 27 separated from the 45 main length or stretch of track by insulation 28-28 and extending around these short rail sections 25, 26 are bond wires 29, 30 similar to bond wires 16, 17 previously described. It is to be understood that at the 50 beginning of block 6 there is a relay similar to the relays 10, 19 above described.

At the end of block 5 there is a track battery 31, one side of which is connected by wires 32, 33 with short rail section 14 and 55 having its other side connected by wire 34, contact point 35, switch 36, wire 37, armature 22, contact point 38, wire 39 to bond wire 17. Also cooperative with the switch 36 is a contact point 40 from which extends 60 a wire 41 to a resistance coil 42, thence by wire 43 to wire 33 and thence to short rail section 14. This switch 36 is operated and controlled in any suitable manner by the signal 44 at the beginning of block 4. The 65 signal is of any approved type arranged to

be set to the three usual positions, "clear", "caution" and "danger" dependent upon the conditions in the block 4 and the block in advance thereof (not shown). For illustrative purposes, a train is assumed to be 70 in a block 4 as is indicated by the wheels and axle 45 spanning the tracks 1 and 2, short-circuiting the battery by which current is supplied to relay 19 and then de-energizing relay 19 causing the armature 22 thereof to fall 75 away from contact point 38 and to break the circuit of battery 31. To correspond with this position, the signal 44 is shown to be at the "danger" position. The signal 44 and the mechanism for operating the same are so arranged as to hold the switch 36 closed against contact point 35 at all times except when it is set to "caution" position. In block 5 is shown the corresponding signal 46 and because of the presence in block 4 of the train 80 45 this signal 46 is at 45° or "caution" position. The connection between signal 44 and armature 46 is such that the armature 36 will be held closed against contact point 35 at all times except when signal 44 is in "caution" position. When it is in "danger" position, the armature 36 will be held closed against the contact point 35 just as it is when the signal 44 is in "danger" position.

Block 6 is likewise provided with a track 95 battery 47, one side of which is connected by wires 48, 49 with short rail section 27 of block 6 and the other side of the battery 47 is connected by wire 50 to contact point 51 cooperating with which is switch 52 connected by wire 53 to armature 18 held by magnet 10 when block 5 is clear against contact point 54 which in turn is connected by wire 55 with bond wire 30. The switch 52 is controlled by the signal 46 or by the 100 mechanism for operating the same and hence the signal is in "caution" position and the switch 52 will be separated from contact point 51 and will rest against contact point 56 which is connected by wire 57 to resistance coil 58 and thence by wire 59 to wire 49 and thence to short rail section 27.

The above constitute the track circuits, that is to say, those circuits which are controlled by stationary batteries along side 115 the track, as distinguished from the train battery and circuits which are carried by the train and are actuated or energized by a battery or batteries also carried by a train, all of which will be described below.

The showing in Fig. 1 of the trucks of the train is to a large extent diagrammatic for the sake of clearly showing the electric circuits carried by the train. A more complete showing of the way in which the circuits are established through the truck is 125 illustrated in Fig. 2. It is desirable in wiring for this system to have one truck at least thoroughly and completely insulated from the car or tender mounted thereon. The 130

truck 60 shown in Fig. 2 and diagrammatically indicated in Fig. 1 comprises a truck bolster 61 which is carried by the wheels 62 running on the tracks 1 and 2. The top of 5 the bolster truck is provided with a steel plate 63 secured rigidly to the truck bolster 61 in any suitable manner but insulated therefrom by a sheet or plate of insulation 64. This sheet or plate of insulation 64 completely separates or spaces the plate 63 from 10 the truck bolster 61 but in the center thereof may be provided a circular hole 65. The truck bolster itself is also preferably provided with a centrally disposed circular hole 15 66 within which is tightly fitted a sleeve 67 of insulating material, said sleeve having preferably a flange 68 at the upper end which readily fits into the circular hole 65 in the sheet or plate of insulating material 20 64.

The steel plate 63 also preferably has therein a hole 69 coaxial with the holes 65 and 66, and within the cylindrical sleeve 67 is driven or otherwise tightly fitted a cylindrical sleeve 70, preferably of steel or wear 25 resisting material, said sleeve being also provided with an outwardly extending flange 71 on one end adapted to fit easily into the hole 69 in the steel plate 63. In describing this construction, the truck bolster 61 is assumed to be of metal. Of course, if it be of wood, the sheet of insulation 64 and the sleeve 67 of insulation might be omitted. As shown in Fig. 2 then, the complete truck 30 bolster comprises the wheels 62, the journal boxes 72, the bolster 61 and the steel plate 63 and steel bushing 70 insulated from the truck bolster 61 by the sheet or plate of insulation 64 and the sleeve 67 of insulating material. The cylindrical sleeve or steel bushing 70 is for the reception of the kingpin 73 by means of which the car or tender 40 is pivotally mounted on the truck bolster.

To the underside of the floor 74 of the car 45 or tender is the tender or car bolster 75, to the underside of which is rigidly secured a steel plate 76 between which and the bolster 75 is interposed a sheet or plate 77 of insulating material. Through the middle of the car or tender bolster 75 is a cylindrical hole 50 78 within which is fitted a bushing 79 of insulating material, the same serving to insulate a steel sleeve 80 from the floor 74 and tender or car bolster 75 as clearly shown in Fig. 2. This steel sleeve 80 preferably passes through a suitable opening in the steel plate 55 76 to substantially engage the flange 71 on the cylindrical sleeve or steel bushing 70 of the truck bolster, the steel plate 76 being held onto the bottom of the car or tender 60 bolster 75 by bolts 81 passing through sleeves 82 and washers 83 of insulating material. It is to be understood that the plate 63 is 65 preferably secured to the truck bolster 61 by bolts or rivets similarly passing through

insulated sleeves and insulating washers as will be readily understood by those skilled in the art.

It is to be also understood that particularly in all steel trains the metal of the train 70 may form and may be used as a ground to which one terminal of a battery may be connected as to earth or ground.

When constructed as above described the truck shown in Fig. 2 and the bolster therefor are completely insulated from the train as is also the king-pin 73. The contacting surfaces of the truck bolster and the car or tender bolster are steel plates 63 and 76 to receive the weight of the car and to take the 80 wear between the truck bolster and the car or tender bolster.

In Fig. 2 I have shown what may be termed the tender truck also indicated as 60 in Fig. 1. I may insulate two trucks of 85 the train and in Fig. 1 truck 84 is indicated as also being insulated, but the construction thereof may be exactly like that shown in Fig. 2 and an illustration thereof is unnecessary except as diagrammatically shown 90 in Fig. 1 wherein the truck wheels 85 support and carry a truck bolster 86 and wherein a car bolster 87 is provided with a metal plate 88 (corresponding to the metal plate 76 of Fig. 2) and said metal plate 88 is insulated from the car bolster 87 and the truck bolster 86 by sheets 89 and 90 respectively, corresponding to the sheets 77 and 64 of insulating material shown in Fig. 2.

The mechanism carried by the train as a 100 part of my automatic apparatus adapted to cooperate with the track apparatus previously described may and preferably consists of a source of air, under pressure, indicated by reservoir 91 connected by a pipe 92 to an 105 electromagnet valve 93, and this valve is connected by a pipe 94 to a second electro-magnetic valve 95. The valve 95 is connected by a pipe 96 to a cylinder 97 within which is piston 98 on the rod 99 on which 110 is a valve 100 in the main air pipe line 101 which communicates with the chamber 102 above the valve 100. The chamber 103 below valve 100 may be connected by a pipe 104 to a cylinder 105 having therein a piston 115 106 adapted to control the throttle valve 107 of the locomotive. If this mechanism be used with an electrically propelled train, the throttle 107 would be replaced by a switch for controlling the operation of the motors 120 of a train. Interposed between the two valves 93 and 95 and connected to the pipe 94 is a pipe 108 connected to a chamber 109 in which is a valve 110 adapted to cooperate with a seat 111 therefor. Said valve 110 is 125 carried by a valve stem 112 on which is an upper valve 113 adapted to cooperate with a valve seat 114. The valve 114 opens or cuts off the upper chamber 115 from a chamber 116 located substantially midway be- 130

between the two valves 110 and 114. Communicating with the chamber 116 is a pipe 117 connected to the pipe 96 and through it to the cylinder 97. Located on the pipe 117 is a pressure controlled valve 118. This valve 118 is so arranged that when the pressure is not far from normal it is held against its seat to hold the small port 119 closed, but when the pressure in the pipe 117 falls below a predetermined point the valve 118 leaves its seat and puts pipe 117 into communication with the atmosphere.

Any suitable form of speed responsive mechanism may be used for controlling the valves 110 and 113, and in Fig. 1 is more or less diagrammatically shown a fly ball governor 120 on which is adjustably mounted an arm 121 adapted to engage at times the upper end of the valve stem 112. This arm 121 preferably carries at its outer end a metal contact finger or bushing 122 insulated from the arm 121 by insulation 123. This finger or bushing 122 is adapted to be moved by the governor 120 over to metal contact plates 124 and 125 insulated from the train and from each other by insulation 126.

The electric circuits for controlling the electro-magnetic valves 93 and 95, and carried by the train, may be and preferably are battery 127 to one side of which is connected the metal plate 76 by a wire 128, said plate 76 being also connected by wire 129 to the electromagnet 130 of the valve 93. From said magnet 130, a wire 131 is preferably grounded to train as at 132. Whenever an electric circuit in this specification is so grounded to train, this "earth" or "ground" is indicated by "Gt." The other side of battery 127 is connected by a wire 133 to the metal truck bolster 61 and is therefore grounded to the rails through the wheels 62 and journal boxes 72. This grounding to rail is indicated in this specification as "Gr" and the battery 127 will always be closed through the ground to train 132 and the ground to rail 134 except when the truck 60 is within one of the short insulated sections 26, 27, as shown in Fig. 2, or 13, 14, or any other one of the short insulated rail sections 50 with which each block is respectively provided near the end thereof as previously described. When, therefore, an insulated truck, such as that shown in Fig. 2 enters the short rail section, as for instance, short rail section 26, the circuit from battery 127 will be broken, the magnet 93 de-energized and the valve 93 permitted to drop unless the magnet 130 thereof be energized from the track battery as will be referred to again 60 below. I prefer to insulate a second truck 84 of the train to the rear of the truck 60 for the purpose of controlling the valve 95 as follows: Carried by the train is a battery 136 which, by wire 137 is connected to plate 88 65 between the truck bolster 86 and the car

bolster 87, said plate also being connected by a wire 138 to magnet 139 of valve 95, the wire 140 leading from the magnet 139 being grounded to train by being connected to wire 131 and thence to ground 132. The other 70 side of the battery 136 is connected by wire 141 to the rail ground 142. This circuit being substantially like the circuit from battery 127 through magnet 130, it will be plain that this circuit from battery 136 through 75 coil 139 will be a closed circuit at all times except when the wheels 85 of truck 84 are in an insulated short rail section, such, for instance, as sections 26 and 27, when said circuit will be normally broken so far as 80 battery 136 is concerned by the insulation 28 which separates the short rail sections from the main stretch of track 1, 2. When the circuit from battery 136 is broken, the magnet 139 is de-energized and the armature 143 85 will fall, thus closing the valve 95 and cutting off pipe 96 from communication with pipe 94 through valve 95.

The magnets 130 and 139 are so wound that the magnet 95 requires more current 90 to hold it up than its magnet 93, the resistance in the magnet 139 being greater than that of magnet 130. This is for the purpose of coacting with the track circuits so that under certain conditions the valve 95 may 95 be closed by reason of the dropping of the armature 143, while valve 93 may be still held open for the purpose of permitting the train to proceed at a low rate of speed as will be referred to below.

It may here be stated that the armature 143 of the magnet 139 is enclosed by a casing 144 so that it may not be manually re-set and that the armature 135 of magnet 130 is preferably located at such a place that it is 105 inaccessible to an engineer until he shall have stopped his train and stepped out of the cab for the purpose of lifting the armature 135 back into the field of the magnet 130. The strength of the magnet 130 is 110 such and the distance of the armature 135 is such, that when the magnet 130 is once de-energized and the armature 135 has dropped it cannot be lifted again by the current flowing through the magnet 130 from the train battery or the track batteries. The magnet 139, however, is so arranged that when once the armature 143 has fallen, neither the battery carried by the train nor the track battery can of itself draw it back 120 to the magnet 139 and thus open the valve 95 but that the combined strength of the track and train batteries will be sufficient to so energize the magnet 139 as to draw it back to the dotted position shown in Fig. 125 2 with the valve 95 open.

The operation of my device is as follows: When in a clear block and running at a high rate of speed, the circuits through magnets 139 and 130 will be closed by the train 130

batteries 136 and 127 respectively; the arm 121 on the governor 120 will be raised as high or higher than the dotted position shown in Fig. 1 wherein the arm 121 is 5 shown above and out of contact with the upper end of the valve stem 112. The finger or brush 122 will be on the plate 124 and out of contact with the plate 125. If now, under these conditions and at that speed 10 the train enters the short insulated rail sections 26 and 27 of block 6 and the signal 46 is as shown in Fig. 1, set to the "caution" position, the external track circuits will be as they are shown at the beginning of block 15 5 in Fig. 1. Armature 18 will be held against contact 54 by relay 10, there being no train in block 5, but switch 52 will be in engagement with contact point 56 being in that position because the signal 46 is at 20 "caution". As truck 60 then enters this block, there will be established the following circuit battery 127 (carried by the train), wire 128, metal plate 76, wire 129, magnet 130, wire 131 to train ground 132 from the 25 train to the rails 1, 2 to the left of the short rail section 26, 27, thence by bond wire 30, wire 55, contact point 54, armature 18, wire 53, switch 52, contact point 56, wire 57, resistance 58, wire 59, wire 49 to short rail 30 section 27, thence by wheels 62, journals 72, truck bolster 61, wire 133 back to battery 127. For convenience, in Fig. 1 this circuit from short track section 26 or 27 back to battery 127 is indicated by a dotted line 35 133' from wheel 62 to wire 133. It will here be seen that the circuit then through magnet 130 will be maintained closed but by reason of the resistance 58 in that circuit, the current will be weaker, sufficient, however to 40 maintain the armature 135 against the magnet 130. It will thus be seen that when a train is about to enter a block at a speed higher than a predetermined fair rate of speed, as, for instance, a speed greater than 45 thirty miles an hour when the signal for the block about to be entered is set at "caution", the circuits are such that the magnet 130 will not be de-energized and the valve 93 will be held in its upper position. When, however, 50 the next insulated truck 84 so enters this same short rail section, the truck 60 will have passed out of it and the magnet 130 will continue to be held energized by the train battery alone as it normally is so 55 energized.

However, when the truck 84 enters this short rail section, the following circuit will be established,—battery 136, wire 137, metal plate 88, wire 138, magnet 139, wire 140, 60 wire 131 to train ground 132, thence to rails 1 and 2 and bond wire 30, wire 55, contact point 54, armature 18, wire 53, switch 52, wire 57, resistance 58, wire 49 to short rail section 27, thence by wheels 85, truck bolster 65 86, back to battery 136 (indicated by dotted line 141' in Fig. 2). The circuit through magnet 139 will not therefore be broken but the strength of the current will be reduced by reason of the presence in the circuit of resistance 58 and this reduction in 70 the amount of current causes the armature 143 to fall from the magnet 139 and to close the valve 95. When the valve 95 closes, the air from pipe 94 to pipe 96 is cut off through valve 95 and the air from pipe 94 75 through pipe 108 to chamber 109 through the seat 11 is closed by valve 110 it being assumed that the train is still running above said speed of said thirty miles an hour and the arm 121 is out of contact with the upper 80 end of the valve stem 112. All air then from the main supply tank 91 is cut off from cylinder 97 under these conditions and air immediately begins to leak out of the pipe 117 through the now open valve 112 and 85 through the upper leak port 145 from the upper chamber 115 above valve 113. When the pressure in this pipe 117 shall have been reduced to be insufficient to maintain the valve 118 on its seat, it will drop away from 90 its seat 119 and all the pressure in pipe 117 will be incidentally reduced to atmospheric. This reduction of the pressure in pipe 117 enables the compressed air in train pipe 101 to force the valve 100 off its seat and passing 95 through pipe 101 enters cylinder 105 and draws the piston 106 to the right, closing the throttle and stopping the train. At the same time that the brakes are applied by reason of the reduction of the pressure in the 100 air brake system pipe 101 in the usual manner. If then one attempts to enter a block in which the signal is at "caution" at a speed higher than a predetermined speed of say thirty miles an hour, the brakes will be 105 applied and the train stopped automatically independent of, and in spite of anything which the engineer can do.

At the said speed of thirty miles an hour, the arm 121 is so adjusted as to just touch 110 the top of valve stem 112 and push the valve 110 off its seat but the contact finger 122 will still be in engagement with the metal plate 124 only; that is to say, it will be out of contact with the metal plate 125. 115

When, therefore, an engineer enters a block in which the signal is set at 45° or "caution" but at the said speed of say thirty miles an hour, then, although the armature 143 of the magnet 139 shall have fallen and the valve 95 shall have closed, air from the air supply tank 91 will still be admitted through pipe 92, valve 93, pipe 94, pipe 108, chamber 109, valve port or seat 111, pipe 117 to cylinder 97 and the air therein 120 will continue to hold the valve 100 on its seat to prevent the air from the train pipe passing therefrom through it. It is to be understood that the leak port 145 is a small one so that the air supplied from tank 91 125

130

will be at such a pressure as to still hold the piston 98 in its elevated position notwithstanding the slight leak through the leak port 145.

- 5 There remains then to describe the action of this apparatus when an engineer attempts to enter a block such as the block 4 when the signal 44 therefor is set at "danger" as shown in Fig. 2. It will be understood that 10 when the tender truck 60 enters the short rail section 13, 14, the circuit from train battery 127 is broken since wire 133 is grounded to rail and the short rail section 13, 14 is insulated by the insulation 15. The rail 15 ground of the battery 127 is then cut off from the train ground by the insulation 15. When the signal is set at "danger" as is the signal 44, the relay 19 has been de-energized by reason of the presence of say a train 45 20 in block 4 and the armature 32 will have fallen away from contact point 38. In any other position than in "caution" position, the switch is held against the contact point 35 just as the switch 52 is always held against 25 the contact point 51 except when the signal is in "caution" position. The track circuit battery 30, wire 32, wire 33 to short rail section 14, wheel 62, track bolster 61, wire 133, battery 127, wire 128, plate 76, wire 129, 30 magnet 130, wire 131 to train ground 132 and thence through the wheels of the train to track 2, bond wire 17, wire 39, contact point 38, armature 22, wire 37, switch 36, contact point 35 and wire 34 back to battery will be 35 broken by the armature 22 falling away from contact point 38. This will then cause the armature 135 to fall permitting the valve 93 to close to cut off all air from tank 91 to pipe 94. The air then in the piping between the valve 93 and the cylinder 97 will leak out 40 through the leak port 145 as well as through the leak port 146 in the casing of valve 93 and when the pressure in the pipe 117 falls a little below the normal pressure required 45 to hold the valve 118 closed, that valve 118 will open reducing pressure in pipe 117 and allowing the pressure in the train pipe 101 to open the valve 100. I have provided, however, a mechanism whereby an engineer 50 may enter a block, the signal to which is set at "danger" and in which there may be another train, provided he does not enter it at or while in it increase his speed over a pre-determined low speed of say four miles an hour. This is provided by a wire 147 connecting the wire 131 from magnet 130 55 through switch 148, wire 149 with plate 124 and a wire 150 extending from plate 125 to truck bolster 61. The arm 121 is so set and 60 the fly balls of the governor are so arranged that when the train is proceeding at a speed of say four miles an hour, the valve 115 is held closed as shown in full lines in Fig. 1 and the finger 122 bridges and forms an electrical contact between the plates 124 and 125.

The engineer has then brought his train down to a speed of say four miles an hour and closes the switch 148. The train circuit from battery 127 will be held closed as follows: battery 127, wire 128, plate 76, wire 129, magnet 130, wire 131, wire 147, switch 148, wire 149 plate 124, finger 122, plate 125, wire 150, truck bolster 61 and thence by wire 133 back to battery 27.

It will now be seen that by reason of the 75 above construction the truck bolster 61 is substantially completely insulated from the parts of the train mounted thereon. The king-pin 73 is completely insulated so that there is no electrical connection from the 80 truck bolster 61 to the train. It will be seen, however, that if for any reason the insulation 77 or 78 should break down, then the battery 127 would be immediately short-circuited and the magnet 130 would become de-energized, allowing the magnet 135 to fall to 85 stop the train. It is also plain that if the insulation 64 of sleeve 67 should fail to insulate the bolster 61 from the metal plate 63 or bushing 70, the battery 127 would be similarly short-circuited and the circuit through the magnet 130 would cease allowing the armature to fall. In this way any breaking 90 down of the insulation and consequent grounding of the wire between the battery 95 127 and its magnet 130 would immediately result in the stopping of the train. The same construction and arrangement are also present in the truck 84 so that any breaking 95 down of the insulation between the battery 100 136 and its magnet 139 producing a ground between the said battery and the said magnet will result in the closing of the valve 95.

There is one further operation which should be briefly described. Whenever a 105 train has entered a block in which the signal therefor is set at "caution" and the armature 143 of magnet 95 has fallen, the engineer may not thereafter speed up his train above thirty miles an hour until he has nearly 110 cleared that block, because the armature 143 is enclosed in the casing 144 where it cannot be tampered with by the engineer. But this armature 143 is so arranged that it does not fall out of the field of magnet 139 when 115 magnet 139 is energized at the same time by the train battery 136 and the contact battery 31. Remembering that when a signal like signal 44 or 46 is set to the "caution" position, then the armature 22 or 18 and the 120 switch 36 or 52 will be respectively held against their contact points 38 or 54 and 35 and 51. After then having reduced the speed to say thirty miles per hour and about to enter a clear block, the magnet 139 will 125 now be energized by the track battery and by the battery carried by the train. This circuit will be (referring to blocks 4 and 5) from track battery 31, wire 32, wire 33, short rail section 14, to wheels 85 to battery 136 130

(shown by dotted line 141'), thence by wire 137, plate 88, wire 138, magnet 139, wire 140, to train ground 132, and thence to rails 1 and 2, bond wire 17, wire 39, contact 88, armature 32, wire 37, switch 36 contact point 35, wire 34, back to battery 31. The strength of both these batteries flowing through the magnet 139 will be sufficient to draw up the armature 143 and open the valve 95 for normal running conditions.

In this way the whole stopping system is protected because if the system were so arranged that the circuits for any reason become short-circuited and such short-circuiting continue to hold the armatures 143 and 135 to their respective magnets, the track circuits would be inoperative to affect the electromagnets and therefore the engineer might proceed at full speed into a block in which the signals are set against him without producing any operation of the automatic train stopping mechanism carried by the train. This insulation of the truck bolster from the train and this insulation of the king-pin and the insulation of the plates 63 and 76 from the train bolster and from the tender or car bolster is effective to insure the reliable and certain action of the stationary track circuit with respect to the circuit carried by the train so that whenever the track circuits are set to indicate "danger" or "caution" signals, the circuits carried by the train will be always in condition to suitably respond to and coact with the track circuits and any wearing out or breaking down of the circuits carried by the train would make it impossible for the engineer to operate the train until the trouble has been located and repaired.

Having thus described my invention, what I claim and desire to protect by Letters Patent is:

1. In a train stopping and speed controlling mechanism comprising an air brake system and an electromagnetic valve which when energized holds the air brake mechanism from applying the brakes and controlling the speed of the train, the combination with an insulated truck insulated from the rest of the train, a battery carried by the train, one side of which is grounded to the track through said insulated truck, and a metallic plate between and insulated from said truck and the rest of the train, the other side of said battery being connected through said insulated plate to said electromagnetic valve and then grounded to a part of the train from which said truck is insulated, whereby any accidental grounding of the circuit between said battery and said valve, short-circuits said valve and actuates said air brake system.

2. In a train stopping and speed controlling mechanism comprising an air brake system and an electromagnetic valve which

when energized holds the air brake mechanism from applying the brakes and controlling the speed of the train, the combination with an insulated truck comprising a truck bolster and car wheels all insulated from the rest of the train, a battery carried by the train, one side of which is grounded to the track through the wheels of said insulated truck, and a metallic plate between and insulated from said bolster and the rest of train, the other side of said battery being connected through said insulated plate to said electromagnetic valve and then grounded to a part of the train from which said truck is insulated.

3. In a train stopping and speed controlling mechanism comprising an air brake system and electromagnetic valve and which, when energized, holds the air brake mechanism from operating, the combination with a truck insulated from the rest of the train, a battery carried by the train, one side of which is grounded to the track through said insulated truck, a metallic plate between and insulated from said truck and said train, the other side of said battery being connected through said insulated plate to said electromagnetic valve and then grounded to a part of the train from which said truck is insulated, a speed-controlled switch normally open but automatically closed whenever the train is proceeding at or slower than a predetermined low speed, and a shunt circuit from said electromagnetic valve to said switch and thence to said battery.

4. In a train stopping and speed controlling mechanism comprising an air brake system and electromagnetic valve and which, when energized, holds the air brake mechanism from operating, the combination with a truck comprising a truck bolster and car wheels all insulated from the rest of the train, a battery carried by the train, one side of which is grounded to the track through the wheels of said insulated truck, a metallic plate between and insulated from said truck and said train, the other side of said battery being connected through said insulated plate to said electromagnetic valve and then grounded to a part of the train from which said truck is insulated, a speed-controlled switch normally open but automatically closed whenever the train is proceeding at or slower than a predetermined low speed, and a shunt circuit from said electromagnetic valve to said switch and thence to said battery.

5. In a train stopping and controlling mechanism, the combination of a track comprising a block and having a short insulated rail-section near the end thereof, a track battery having one side connected to said short rail section, and the other side connected to the track on each side of said short

rail section, a signal, means to close a partial circuit from the rails to said battery and thence to said short insulated track section when said signal is "clear," to break said partial circuit when said signal is "danger," and to close a partial circuit from the rails to said short rail section around said battery and through a resistance when said signal is "caution," an air brake system carried by the train, an electromagnetic valve which, when energized, holds said air brake mechanism from operating, a truck insulated from the rest of the train, a battery carried by the train, one side of which is grounded to the track through said insulated truck, and a metallic plate between and insulated from said truck and the rest of the train, the other side of the battery carried by the train being connected through said insulated plate to said electromagnetic valve and then grounded to a part of the train from which said truck is insulated.

6. In a train stopping and controlling mechanism, the combination of a track comprising a block and having a short insulated rail-section near the end thereof, a track battery having one side connected to said short rail section, and the other side connected to the track on each side of said short rail section, a signal, means to close a partial circuit from the rails to said battery and thence to said short insulated track section when said signal is "clear", to break said partial circuit when said signal is 35 "danger", and to close a partial circuit from the rails to said short rail section around said battery and through a resistance when said signal is "caution", an air brake system carried by the train, an electromagnetic 40 valve which, when energized, holds said air brake mechanism from operating, a truck having a bolster and wheels all insulated from the rest of the train, a battery carried by the train, one side of which is grounded 45 to the track through the wheels of said insulated truck, and a metallic plate between and insulated from said truck and the rest of the train, the other side of the battery carried by the train being connected through 50 said insulated plate to said electromagnetic valve and then grounded to a part of the train from which said bolster is insulated.

7. In a train stopping and controlling mechanism, the combination of a track comprising a block and having a short insulated rail-section near the end thereof, a track battery having one side connected to said short rail section, and the other side connected to the track on each side of said short rail section, a signal, means to close a partial circuit from the rails to said battery and thence to said short insulated track section when said signal is "clear", to break said partial circuit when said signal is "danger", and to close a partial circuit from

the rails to said short rail section around
said battery and through a resistance when
said signal is "caution", an air brake sys-
tem carried by the train, an electromagnetic
valve which, when energized, holds said air
brake mechanism from operating, a truck
having a bolster and wheels all insulated
from the rest of the train, a battery carried
by the train, one side of which is grounded
to the track through the wheels of said insu-
lated truck, a metallic plate between and
insulated from said truck and the rest of the
train, the other side of the battery carried
by the train being connected through said
insulated plate to said electromagnetic valve
and then grounded to a part of the train
from which said bolster is insulated, a
second electromagnetic valve cooperating
with said air brake system and with said
outside or track circuit when said signal is
at "caution", a second truck insulated from
the rest of the train, a second battery car-
ried by the train, one side of which is
grounded to the track through said insu-
lated truck, and a metallic plate between and
insulated from said second truck and the
train, the other side of said second battery
being connected through said second insu-
lated plate to said second electromagnetic
valve and thence grounded to a part of the
train from which said second truck is insu-
lated.

8. In a train stopping and controlling mechanism, the combination of a track comprising a block and having a short insulated rail-section near the end thereof, a track battery having one side connected to said short rail section, and the other side connected to the track on each side of said short rail section, a signal means to close a partial circuit from the rails to said battery and thence to said short insulated track section when said signal is "clear", to break said partial circuit when said signal is "danger", and to close a partial circuit from the rails to said short rail section around said battery and through a resistance when said signal is "caution", an air brake system carried by the train, an electromagnetic valve which, when energized, holds said air brake mechanism from operating, a truck having a bolster and wheels all insulated from the rest of the train, a battery carried by the train, one side of which is grounded to the track through the wheels of said insulated truck, a metallic plate between and insulated from said truck and the rest of the train, the other side of the battery carried by the train being connected through said insulated plate to said electromagnetic valve and then grounded to a part of the train from which said bolster is insulated, a second electromagnetic valve cooperating with said air brake system and with said outside or track circuit when said signal is 130

at "caution", a second truck comprising a truck bolster and car wheels all insulated from the rest of the train, a second battery carried by the train, one side of which is 5 grounded to the track through the wheels of the said insulated truck, and a metallic plate between and insulated from said second truck and the train, the other side of said

second battery being connected through said second insulated plate to said second electro- 10 magnetic valve and thence grounded to a part of the train from which said second truck is insulated.

In witness whereof, I have hereunto set my hand this eleventh day of May, 1922.

FRANK C. WILLIAMS.
